(57) **CLAIM**

The ornamental design for a baffle for food waste disposer, as shown and described.

DESCRIPTION

FIG. 1 is a top perspective view;
FIG. 2 is a bottom perspective view;
FIG. 3 is a top view;
FIG. 4 is a bottom view;
FIG. 5 is a left side view;
FIG. 6 is a right side view;
FIG. 7 is a front side view; and,
FIG. 8 is a rear side view.
